CLEANING MECHANISM

William G. Wallenbeck, Chicago, Ill.

Application August 24, 1931. Serial No. 558,915

7 Claims. (Cl. 15—121)

My invention relates to an improved construction of cleaning mechanism applicable to a variety of cleaning operations, for example, to cleaning operations generally where surfaces 5 that are flat, or nearly so, are to be washed with water and the water is to be removed after the washing operation, as in the case of washing windows, and in numerous other cases where the cleaning is to be effected by moving the 10 cleaning medium in dry condition over the surface to be cleaned, as in the case of cleaning painted walls or wall paper.

By my invention, I provide an improved construction of holder for cleaning pads of suitable 15 kind, for example sponge rubber pads, so that the pads may be quickly mounted on the holder and effectively clamped to it, so that any desired cleaning operation may be effectively accomplished by means of the cleaning pad.

20 More specifically, my improved holder construction consists of a form around which the cleaning pad may be wrapped, which form is rigid or substantially so, and clamping devices on each side of the shank of the form, each 25 adapted to engage one end of the cleaning pad, to the end that the cleaning pad may be snugly held around the form. The clamping devices are preferably of an overall thickness somewhat less than the corresponding thickness of the 30 form, as a result of which practically the entire outer surface of the cleaning pad is available for cleaning purposes. It is desirable that a suitable cleaning pad be selected for the particular cleaning operation to be performed. For

35 example, where the cleaning mechanism is to be used for washing windows, a cleaning pad is selected that will readily hold water in considerable quantity, whereas for cleaning walls in dry condition, a cleaning pad is selected that will 40 in dry condition effectively engage the grime and dust on the wall and not only remove the same from the wall, but retain it in and on the pad. My improved cleaning mechanism also includes

45 a novel form of squeegee construction which may be used with the cleaning pad, where the cleaning operation is one involving the use of water, the supporting member of the squeegee construction being conformed to be engaged and held by one of the clamps of the device, so that 50 one side of the cleaning mechanism may be used for washing the surface to be cleaned, while the other side, supporting the squeegee construction, may be used to remove the water from the surface being cleaned. In other cases, where the 55 cleaning pad is used in dry condition, the

squeegee construction is not used, and practically the entire outer surface of the cleaning pad is available for cleaning purposes.

By my invention, I preferably construct the holder for the cleaning pads, of sheet metal so 60 that the form supporting the cleaning pad, the clamping devices, and the shank of the holder are of simple and cheap construction, effectively and simply held together, at the same time providing a structure which positively holds the 65 cleaning pad and permits its effective use.

My invention will best be understood by reference to the accompanying drawing showing a preferred embodiment thereof, in which

Fig. 1 shows my cleaning mechanism in front 70 elevation with the squeegee construction in place thereon.

Fig. 2 is a vertical, sectional view to an enlarged scale, of the parts shown in Fig. 1 taken 75 along the line 2—2,

Fig. 3 is a horizontal, sectional view of a part of the construction shown in Fig. 1, taken along the line 3—3,

Fig. 4 is a vertical, sectional view of a part 80 of the construction shown in Fig. 2, taken along the line 4—4,

Fig. 5 shows in a view similar to Fig. 1, the cleaning mechanism with the squeegee construction removed, and

Fig. 6 shows in plan view, one of the cleaning pads I prefer to use in connection with my 85 cleaning mechanism.

Similar numerals refer to similar parts throughout the several views.

As shown in Figs. 1 and 2, the holder for supporting the cleaning pads, consists of a sheet metal form 10 having side members 10a of curved cross section, connected by a flat base portion 10b. The side members 10a are provided with extending ribs 10c adjacent the base member 10b, to facilitate clamping the cleaning pad around the form 10 in a manner to be described. The form 10, is supported by a shank 11 consisting preferably of two similar sheet metal parts, 11a, 11a, shaped to form a 90 tapered tube to receive a handle, when it is desired to use the cleaning mechanism at locations out of convenient reach of the operator, the shank 11 serving as a handle for the mechanism when the surfaces to be cleaned are within convenient reach. Between the tapered tubular portion of the shank 11, and the base 95 10b, the shank is flattened, and is provided at its end with tongues 11b extending through slots therefor in the base portion 10, said 100 105 110

tongues being pressed tightly against the surface of the base portion 10b as indicated, in which position they are securely retained by second tongues 10d formed from the base portion 10b and pressed tightly against the tongues 11b. In this manner, the form 10 and the shank 11 are securely held together. The portions 11a of the shank 11 are preferably held together by a rivet 12 adjacent the outer end 10 of the flattened portion of the shank, and the outer end of the shank is held together and reinforced by a metal ring 13 which may be secured to the shank portions 11a, 11a in any suitable manner, for example by soldering or 15 brazing.

Adjacent the base portion 10b, the shank 11 has mounted on its flat faces, clamping plates 14, 14, each of which is provided with a clearance slot 14a to receive a rivet 15 which holds 20 the clamping plates in place on the shank 11 and permits their free movement longitudinally on the shank. Each of the clamping plates 14 is provided adjacent its upper edge, with an offset portion, terminating in an upwardly extending flange 14b for engaging an end portion of the cleaning pad 16 which is held in place on the form 10. The flanges 14b are disposed just inside of the ribs 10c, so that when the clamping plates are forced towards the base 25 portion 10, the end portions of the cleaning pad 16 are tightly held between the flanges 14b and the ribs 10c. The rivet 15 also supports locking bars 17, 17 which are pivotally mounted on said rivet, which bars preferably have rounded 30 upper ends and are so proportioned that when they are in alignment with the shank 11, the clamping plates 14, 14 are tightly held in engagement with the cleaning pad 16, by the engagement of the upper ends of the bars with 35 the offset portions of the clamping plates. When the bars are turned to their horizontal position, indicated by dotted lines in Figs. 1 and 5, the clamping plates 14 are released and 40 may be moved away from the base portion 10b to release the cleaning pad and permit the ready removal of the pad and the insertion of the same or another pad as desired. As indicated in Fig. 3, the lower ends 17a of the bars 45 17, are formed to fit the upper end portion of the tapered tubular portion of the shank 11, which tends to hold the bars in their locking 50 position, which in turn holds the clamping plates in their clamping position.

The squeegee member consists of a plate of 55 sheet metal 18 which is curved to surround one edge portion of the cleaning pad 16 when in place on the holder, the upper edge portion of the plate being provided with a groove 18a in which a strip of rubber 19 is tightly clamped, 60 the upper edge of the sheet 18 being extended nearly to the edge of the rubber strip, as indicated at 18b to afford support for the rubber strip during its operation. The sheet 18 is provided with a second transverse groove 18c adjacent its lower edge, for engaging one of the flanges 14b when the squeegee construction is 65 used, the plate 18 being then located between the flange 14b and the adjacent portion of the cleaning pad 16. As a result of this construction, the squeegee construction is securely held in place at one side of the pad 16, when it is desired to make use of it in connection with 70 cleaning operations involving the use of water. As indicated in Fig. 4, the base portion 10b is preferably provided with corrugations 10e

extending between the curved portions 10a, 10a, to stiffen the said base portion.

As a result of the above, it will be observed that my construction is simple and cheap to make, and effective in use. Furthermore, the 80 construction described may readily be adapted to any form, size and construction of cleaning pad, as desired.

While I have shown my invention in the particular embodiment above described, it will be understood that I do not limit myself to this exact construction as I may employ equivalents known to the art at the time of the filing of this application without departing from the 85 scope of the appended claims.

What I claim is:

1. In a cleaning mechanism, the combination of a support comprising a base portion of sheet metal having flanges curved towards each other, a shank secured to said base portion, said shank having flattened sides adjacent said base portion, slotted clamping plates movable on said flattened sides towards and from said base portion, locking bars for operating and holding said plates in clamping position, said clamping plates having outwardly extending portions engaged by said locking bars, and a pivot rod extending through said bars and said shank and also through the slots in said clamping plates, and a cleaning pad held around said curved flanges and against said base portion by said clamping plates.

2. In a cleaning mechanism, the combination of a support comprising a base portion of sheet metal having flanges curved towards each other, a tapered and tubular shank secured to said base portion, said shank having flattened sides adjacent said base portion, slotted clamping plates movable on said flattened sides towards and from said base portion, locking bars for operating and holding said plates in clamping position, said clamping plates having outwardly extending portions engaged by said locking bars, and a pivot rod extending through said bars and said shank and also through the slots in said clamping plates, and a cleaning pad held around said curved flanges and against said base portion by said clamping plates, each of said locking bars being rounded at one end to engage the corresponding clamping plate and curved laterally at its other end portion to fit the smaller end of the tapered portion of said shank.

3. A holder for cleaning pads comprising the combination of a sheet metal base having edge portions constituting a pad support, a shank secured to said base, movable clamping plates for holding a pad against said base, and locking bars for holding said plates in clamping position, said clamping plates having outwardly extending portions engaged by said locking bars to operate said clamping plates.

4. A holder for cleaning pads comprising the combination of a sheet metal base having edge portions constituting a pad support, a shank secured to said base, movable clamping plates for holding a pad against said base, locking bars for holding said plates in clamping position, said clamping plates having outwardly extending portions engaged by said locking bars to operate said clamping plates, and a pivot rod extending through said bars and said shank.

5. A holder for cleaning pads comprising the combination of a sheet metal base having edge portions constituting a pad support, a shank se-

- cured to said base, movable clamping plates for holding a pad against said base, locking bars for holding said plates in clamping position, said clamping plates having outwardly extending portions engaged by said locking bars to operate said clamping plates, and a pivot rod extending through said bars and said shank, said plates having slots therethrough, and said rod extending also through said slots.
- 5 6. A holder for cleaning pads comprising the combination of a sheet metal base having flange portions constituting a pad support, a shank secured to said base, and clamping plates for holding a pad on said support, said shank having end tongues extending through and bent against said base, and said base having second tongues holding said end tongues in place.
- 10
- 15

7. In a cleaning mechanism, the combination of a pad support comprising a sheet metal base portion having integral flanges extending in substantially parallel relation and in the same direction from said base portion, the outer portions of said flanges having curved conformations and extending towards each other, a cleaning pad wrapped around said flanges and having its edge portions resting against said base portion, clamping devices holding the pad edge portions against said base portion, and a handle extending away from said base portion.
